Primary Examiner — Dana K Weiland*Assistant Examiner* — Messina L Smith(57) **CLAIM**

We claim the ornamental design for a wearable microphone, as shown and described.

DESCRIPTION

FIG. 1 is a top perspective view of a wearable microphone in accordance with the present design.

FIG. 2 is a top view thereof.

FIG. 3 is a bottom view thereof.

FIG. 4 is a right side view thereof.

FIG. 5 is a left side view thereof.

FIG. 6 is a front view thereof; and,

FIG. 7 is a rear view thereof.

The dashed broken lines in the Figures show portions of the wearable microphone that form no part of the claimed design.
